Primary Examiner — T. Chase Nelson(74) *Attorney, Agent, or Firm* — DASCENZO Intellectual Property Law, P.C.**CLAIM**

I claim the ornamental design for a footwear outsole tread, as shown and described.

DESCRIPTION

FIG. 1 is a perspective view of a footwear outsole tread showing the new design.

FIG. 2 is a bottom plan view of the footwear outsole tread showing the new design.

FIG. 3 is left side view of footwear outsole tread showing the new design.

FIG. 4 is a right side view of the footwear outsole tread showing the new design.

FIG. 5 is a front view of the footwear outsole tread showing the new design; and,

FIG. 6 is a rear view of the footwear outsole tread showing the new design.

The broken lines shown in the drawings are to illustrate environment, namely, portions of a footwear outsole bearing the claimed design, and form no part of the presently claimed design. The top surface of the footwear outsole and of the new design form no part of the claimed design. The shading lines shown in the drawings represent the approximate three-dimensional contour of the design, and are not intended to indicate surface decoration.
